PLAY TABLE

Erwin R. Culley and Marie W. Culley,
Chicago, Ill.

Application June 1, 1945, Serial No. 597,138

1 Claim. (Cl. 155—123)

1

The invention relates to an infant's table, and more especially to a play table having guard means and an improved rotatable seat for children.

The primary object of the invention is the provision of a table of this character, having a rotatable seat, wherein an infant or child can be safely penned, with access to the table top, so that he or she can maneuver play-things without these getting out of reach, and in this manner, pacifying such child or infant, without attendance by a grown-up, and eliminating the danger of injury.

Another object of the invention is the provision of a table of this character, wherein greater play area is afforded than is provided through the use of an infant's high chair, and in addition, my invention makes it possible for the easy feeding of the infant, without the chance of accidental upsetting of the food containers by the latter, or knocking these from the table.

A further object of the invention is the provision of a table of this character, which is especially designed for infant's use, giving the latter freedom of action while seated, and wherein the table has an improved guard or fencing rim and is readily portable and is foldable to a compact object when not in use.

A still further object of the invention is the provision of a table of this character, which is simple in construction, thoroughly reliable and efficient in its operation, and is strong, durable, neat and attractive in appearance, and wherein an improved seat is rotatable with respect to the table and can be latched in a fixed position. Furthermore, my invention is compact, eliminates the services of an attendant for the infant, affords maximum play space for the latter, and is inexpensive to manufacture.

With these and other objects in view, the invention consists in the features of construction, combination and arrangement of parts as will be hereinafter more fully described, illustrated in the accompanying drawing, which shows the preferred embodiment of the invention, and pointed out in the claims hereunto appended.

In the accompanying drawing:

Figure 1 is a perspective view of the table constructed in accordance with the invention;

Figure 2 is a vertical sectional view therethrough with an infant in occupying position;

Figure 3 is a top plan view;

Figure 4 is a detail view in plan, showing the manner of suspension of the chair or seat for the infant;

2

Figure 5 is a fragmentary sectional view on an enlarged scale taken on the line 5—5 of Figure 3 looking in the direction of the arrows but showing seat and back rest in elevation;

5 Figure 6 is a top plan view of a modified form of my invention, wherein the chair is attached to and supported by an anti-frictionally mounted support carried beneath the table top;

Figure 7 is a section on the line 7—7 of Figure 6 but showing seat and back rest in elevation;

10 Figure 8 is a section on the line 8—8 of Figure 6, and

Figure 9 is a detail of the latching device to prevent rotation of the chair.

15 Similar reference characters indicate corresponding parts throughout the several views in the drawing.

Referring to the drawing, A designates generally a table in its entirety constructed in accordance with the invention, and comprises a top panel 10, supporting at its four corners foldable legs 11, which are pivoted at 12, for folding and unfolding movements, these pivots 12 being attached to part of a fencing rim 13 marginally below the top panel, and marginally above the top panel as at 13a said rim provides a guard rail. The legs 11 have associated therewith pivoted angular braces 14, slidably connected to the top panel 10 in the ordinary well-known manner.

20 25 30 The legs 11 carry swiveled caster rollers 15, to facilitate the rolling of the table from place to place, as may be desired.

35 Formed centrally in the top panel 10 is a circular opening 16 for a ring-like turning hoop 17, which is rotatably oriented at 18 to the edge of the opening 16, and is flush with the top panel and rising through the opening is a chair or seat 19 for an infant. The chair or seat 19 is rotatably fitted to a pedestal 20, having its base 21 fixed to a supporting shelf 22 stationarily hung in downwardly and inwardly angled suspension straps 23, which are made fast at their outer ends to the under side of the top panel 10 at the four corners thereof.

40 45 The back 24 of the chair or seat 19 has fixed connection with a depending flange 25 on the hoop 17, so that these turn together, whereby an infant when occupying the chair or seat 19 can alter his or her facing position or an attendant can do so at will.

50 55 The chair or seat 19 is fitted with a latch, for locking it against rotation, if desired, and which is fully described and shown with reference to Figures 7 and 9. The top panel 10 may be ornamented in any desirable manner, if desired, to

lend attractiveness to the table, and for observation by the infant when using the table A.

The top panel 10 gives maximum play space thereon for an infant when occupying the chair or seat 19, and the said infant can be readily fed from this panel, but the guard rail 13 prevents knocking of toys, plates and the like from the top panel, and the infant is properly elevated by the chair or seat with relation to the top panel.

In the modified form of my invention shown in Figures 6, 7, 8 and 9, the table top panel 10 has an opening 16 and a guard rim or rail 13 similar to that shown in the principal form. However, the rail 13 is extended considerably below the table top as at 26, and in addition to pivotally supporting the foldable legs 11, the part 26 of the rail below the top panel has bolted thereto as at 27 a supporting frame 28 having radial supporting legs 29 attached at the corners and extending to a circular channeled rim 30 beneath the table top and of greater diameter than the opening 16. The rim has a ball race 31 formed therein, in which are mounted balls 32 of an anti-friction bearing, and another ring element 33 is attached to the rim by bolts 33a and seats in the channel 34 of the rim 30 whereby the balls operate between the rim 30 and element 33 and the other anti-friction bearing element 35. The element 35 has a sleeve-like part 36 which is flush with the inner edge of the opening 16 and has bolted thereto as at 37 the infant's chair 38. By these means, the chair is rotatably mounted with reference to the table and movement is facilitated by the anti-friction mounting. To latch the chair in a fixed position, I provide a latch pin 39 in a keeper 40 attached to the rim 30 which is spring-pressed to a latching position by spring 41. The pin has a curved shank 42 which is pivotally connected as at 43 near one end of a rotatable arm 44 on the bracket 45, to the other end of which is pivotally connected the curved end 46 of an operating rod 47 extending through a friction stop device 48. Any suitable friction stop or clamp, generally indicated at 48, may be employed to engage the rod 46 to prevent accidental release of the latch pin 39 from the sleeve-like part 36 of the bearing element 35. If desired, depressions may be provided in the part 36 to receive the end of the pin, or the pin may be provided with a rubber tip foot 50 to function as a friction brake.

What is claimed is:

An infant's table and seating device, comprising a table top, a guard rim about the table top and extending below the top, a support member attached to the rim, the table top having a circular opening located centrally thereof, a second member beneath said table top and attached to said member support, said members having an opening in alignment with and of a greater diameter than said table top opening, a channel-shaped raceway in said members, anti-friction means carried by said raceway, a hollow cylindrical chair-supporting member within said members and extending from below said table top to substantially below the lower edges of said support member, said chair-supporting member having an internal diameter substantially equal to that said table top opening whereby said table top overlaps said chair-supporting member, an annular portion integral with and intermediate the ends of said chair-supporting member, said chair-supporting member being rotatably supported in said raceway by said anti-friction means, a chair fixed to said chair-supporting member and within said member whereby said chair is rotatably mounted relative to said support and a latch device secured to said support and adapted to engage said chair-supporting member to prevent rotation of the chair.
